METHOD AND APPARATUS FOR GROUTING

John P. Hartman, Fort Peck, Mont.

Application May 28, 1938, Serial No. 210,782

7 Claims. (Cl. 61—36)

(Granted under the act of March 3, 1883, as amended April 30, 1928; 370 O. G. 757)

This invention described herein may be manufactured and used by or for the Government for governmental purposes, without the payment to me of any royalty thereon.

This invention relates generally to grouting, but more particularly to a grouting tool and the method of using the same.

One object of the invention is to provide a multiple jet grouting tool adapted to cut through the subsoil with a combined jetting and sawing action.

Another object of the invention is to provide a grouting tool with interchangeable nozzles adapted to produce jets of any suitable diameter, or to provide for the renewal of nozzles when they become clogged or worn.

Another object of the invention is to provide a grouting tool which is of simple, economical and durable construction, and one which may be easily operated and cleaned.

Another object of the invention is to provide a method for hydraulically cutting away the subsoil with a sawing action and forming an impervious curtain in the cut area.

A further object of the invention is to provide a method and means for producing a uniform and continuous grouted volume in the locality desired and one which will be impervious to the seepage of water.

The invention which forms the subject matter of this application relates to a method and means of grouting gravels, sands, silts and mixtures thereof, in which the grouting solution or suspension is introduced under pressure in a manner resulting in the flotation of the material being grouted immediately surrounding the grouting tool.

Certain types of soil are very difficult to grout, although they are quite pervious for a flow of water. The difficulty arises whenever the maximum dimension of the pores of the soil is less than the diameter of minimum dimension of the grout particles, as the grout particles cannot penetrate into the pores regardless of the applied pressure unless some action takes place to enlarge the pore openings. In many cases the enlargement of the pores to permit penetration of the grout produces detrimental effects in the original structural conditions of the adjacent property. It is also practically impossible to control the volume to be grouted.

The flotation process of grouting enlarges the pore space temporarily within definite controllable limits until the grout can penetrate,

after which the setting soil particles trap the grout particles in the soil pore spaces.

The improved method and apparatus for effecting grouting operations may be utilized in the following forms of engineering work:

Grouting of foundations for all types of structures;

Grouting around caissons, cribbings and coffer dams;

Grouting of earth, dams, levees and dikes; 10

Grouting cores in earth dams, levees and dikes constructed of gravel, sand, silt and mixtures thereof, parallel to the axis of the structures after the complete placement of earth fill;

Grouting of material where it is not necessary 15 to grout large areas, but merely to form cut-off curtains.

Referring more particularly to the accompanying drawing in which corresponding parts are indicated by similar reference characters:

Fig. 1 is a front elevation of the grouting saw;

Fig. 2 is a side centrally sectionized elevation of the grouting saw;

Fig. 3 represents a section taken on the line 3—3 of Fig. 2; 25

Fig. 4 is an enlarged top plan view of one of the nozzles, as illustrated in Fig. 1;

Fig. 5 is an enlarged sectionized view of a nozzle, as shown in Fig. 2;

Fig. 6 is a side elevation of a tractor provided 30 with a reciprocating apparatus for operating the saw.

The grouting device or saw consists of a pipe 10, composed of metal or other suitable material, pointed at one end and equipped with a series of nozzles 11 extending longitudinally in a straight line throughout its length. The pipe may be circular in shape, although those having oval or streamlined sections, as shown in Fig. 3, are preferred. The nozzles 11 through which the grout is forced, as will be further described, are formed with a hexagonal head 12 adapted to fit a wrench and a slightly tapered and externally threaded body portion 13 adapted to fit threaded holes 14 in the pipe. 45

The nozzles are dimensioned so as to be interchangeable in order to expedite replacement after excessive wear, and also by varying the size of their internal passage 15, adjustments can be made to adapt the equipment to the type and volume 50 of the grouting material.

A smaller pipe 16 is welded or otherwise fastened to the main pipe 10 throughout its length and diametrically opposite to the longitudinal row of nozzles 11. This small pipe 16 is for the 55

passage of water under pressure, and is used to jet the main grout pipe 10 into the material to be grouted.

The grout consisting of bentonite or other suitable material is pumped into the main grout pipe 10 under pressure and is expelled therefrom through the nozzles 11. By proper spacing of the nozzles and by using sufficient pressure on the grout, the material immediately in front of the nozzles and some of the material surrounding the grouting pipe is floated, resulting in a quicksand condition.

By employing a mechanism for producing a reciprocating motion, and to which the upper flange 17 of the grouting pipe 10 may be attached, such as the mechanism shown on the tractor illustrated in Fig. 6, it is possible to move the grouting pipe or saw vertically as it progresses horizontally through the material to be grouted in the direction of the nozzle jets, the action being similar to that of sawing. As the horizontal movement progresses, the sand behind the pipe being no longer floated, settles, trapping the grout in the pores of the material. This method of grouting forms definite grouted volumes the sizes of which are functions of the size grouting equipment and the pressures used.

In carrying out the method for grouting with the saw described above a suitable tractor mounted operating mechanism is provided. This mechanism comprises a reciprocating supporting tube 18 slidably mounted in a supporting bracket 19 and connected by a link 20 to an oscillating rocker arm 21. The rocker arm 21 is pivotally mounted on a shaft 22 which is in turn mounted in two supporting brackets 23, only one of which, is shown. In the illustration shown in Fig. 6, it will be noted that the rocker arm 21, is provided with a slot 25 which slidably receives the rectangularly projecting pin 26 of the crank arm 27.

The crank arm 27 is connected to a rotating shaft 28 which is operated through gears connected to the tractor motor and which are not shown in the illustration. The motor is adapted to effect a reciprocating motion of supporting tube 18 which is imparted to the saw 10 to which it is connected through its lower flange 31 and flange 17 of the grouting pipe or saw.

As the tractor moves along the surface of the terrain the pipe or saw 10 which has been sunk into the subsoil is given a reciprocating motion by the mechanism described above, as bentonite or other suitable grouting material is pumped through the flexible tube 29 and supporting tube 18 into the interior of the grouting pipe or saw 10, and out through the nozzle 11, as shown in Fig. 6. The pipe 16, which is attached to the saw 10 is connected to a water supply (not shown) through the flexible tube 30. The pipe 16 is of great advantage in sinking the saw as described above.

Having described my invention, what I claim as new and wish to secure by Letters Patent is:

1. A grouting saw comprising an ejecting pipe for conveying grouting material provided with a longitudinal row of ejector nozzles, and a longitudinally aligned pipe of smaller diameter for conveying water, arranged diagonally opposite said nozzles and terminating with an outlet opening at the end of said ejecting pipe. 5

2. In a grouting apparatus the combination with an internally bored grouting tool, means for imparting a vertical and a longitudinal movement 10 to the tool, a source of cementitious material in communication with the bore of the tool, and means for discharging the material from the bore in the form of a plurality of streams.

3. In a grouting apparatus the combination 15 with an internally bored grouting tool, means for imparting a vertical and a longitudinal movement to the tool, a source of cementitious material in communication with the bore of the tool, and means including a series of aligned openings for 20 discharging the material from the bore in the form of a plurality of superimposed streams.

4. In a grouting apparatus the combination 25 with an internally bored grouting tool, means for imparting a vertical and a longitudinal movement to the tool, a source of cementitious material in communication with the bore of the tool, and means in connection with the tool for discharging said material from the bore in the direction of the longitudinal movement of the tool and in the 30 form of a plurality of superimposed streams, said means including a series of vertically spaced nozzles.

5. In a grouting apparatus the combination 35 with a grouting tool including an ejector and an irrigating tube; of means for imparting a vertical and a longitudinal movement to said tool, a source of cementitious material in communication with said ejector tube, a source of water supply connected to said irrigating tube, means including a 40 plurality of vertically spaced nozzles for discharging the material from said ejector tube in the form of a plurality of parallel vertically spaced streams and in the direction of the longitudinal movement of the tool, and means for directing a 45 stream of water from the irrigating tube in the direction of its vertical movement.

6. A grouting process for forming a subsoil wall consisting in linearly directing a series of superimposed streams of cementitious material through 50 said subsoil, and simultaneously imparting a vertical movement to said streams.

7. A grouting process for forming a subsoil wall substantially impervious to moisture consisting in irrigating the subsoil with a downwardly directed 55 jet of water and at the same time linearly directing a series of superimposed streams of cementitious material through the subsoil, while imparting a reciprocating and a longitudinal movement to said streams.

JOHN P. HARTMAN.
